(57) **CLAIM**

The ornamental design for a luminaire, as shown and described.

DESCRIPTION

FIG. 1 is a top, front and right side perspective view of the luminaire of the present invention;

FIG. 2 is a left side view thereof;

FIG. 3 is a front view thereof;

FIG. 4 is a right side view thereof;

FIG. 5 is a rear view thereof;

FIG. 6 is a top view thereof, shown at an enlarged scale from FIG. 1; and,

FIG. 7 is a bottom view thereof, shown at an enlarged scale from FIG. 1.

The broken lines showing environmental structure are for illustrative purposes only and form no part of the claimed design.

1 Claim, 7 Drawing Sheets
